PACKAGE AND CLOSURE

Eino E. Lakso, Fitchburg, Mass., assignor to Vogt
Processes, Incorporated, Louisville, Ky., a cor-
poration of Delaware

Application January 9, 1935, Serial No. 991

4 Claims. (Cl. 229—5.5)

My present invention relates to the packaging of plastic material such as ice cream or the like and involves a cylindrical container of paper, cardboard or other fibrous material having a removable flanged cap which may be conveniently manually telescoped over the end of a container and which imposes sufficient frictional resistance to withdrawal, to insure the retention and proper positioning during shipment and storage.

5 A feature of the invention is the provision of a container cap or closure embodying a container-embracing flange adapted to be placed under circumferential tension as an incident of applying the cap and which consists of an annulus of fibrous material folded upon itself to afford a circular radially yielding flap so designed that as the cap is applied to the container, the container mouth cams into the flap, expanding it and placing it under tension so that it offers a substantial frictional resistance to removal.

10 Another feature of the invention is the provision of a container closure of the general character described above which is of extremely simple, practical, rugged, durable and efficient construction capable of being inexpensively manufactured and consisting merely of a circular closure portion and an annular container-engaging flange-forming member interlocked with the circular closure portion and having its lower edge bent inwardly and upwardly to define the frictional flap. The upper edge of the flange forming member is bent inwardly and downwardly and the disk-like closure member is locked between the oppositely and inwardly directed edges 15 of the flange-forming piece.

15 My improved cap forms a part of my improved package. The relatively light cylindrical shell may be completely filled with ice cream or other plastic material and is thereby reinforced by the cream to such an extent that flexure of the yielding flap of the closure with consequent substantial frictional grip occurs when the cap is forced home. This is in contradistinction to the application of the cap over the mouth of a light unfilled shell where the shell being more flexible than the closure would do most of the yielding itself and but light frictional contact would be had.

20 Furthermore the disk of my improved closure is of a diameter greater than the mouth of the cylindrical shell to be capped and lies flatly against said mouth, contacting its entire periphery when the cap is applied. With the container brim full of plastic or frozen material directly contacting the disk of the closure, a sub-

stantial vacuum effect is created to oppose removal of the cap, the force supplementing the frictional drag of the closure flap against the outer surface of the shell.

25 The invention may be more fully understood from the following description in connection with the accompanying drawing wherein:—

Fig. 1 is a perspective view of a cylindrical container with my improved closure in applied position,

30 Fig. 2 is an enlarged broken transverse sectional view through the closure removed from the container,

Fig. 3 is a view similar to Fig. 2 but showing the manner in which the container mouth cams 15 into the tapered annular flap of the closure,

35 Fig. 4 is a view similar to Fig. 2 with the closure fully telescoped over the mouth of the container and with the container completely filled with ice cream, and

40 Figs. 5, 6 and 7 are views corresponding to Figs. 2, 3 and 4 respectively but illustrating a slightly modified form of closure.

In Fig. 1 I have illustrated a type of fibrous container 20 consisting of a side wall cylindrical throughout its length and having a bottom 21 secured thereto in any conventional or convenient manner and preferably in such fashion that it is liquid tight. The container may be of light stiff cardboard or other material suitable for the purpose and adapted to encase a partially or fully frozen mass of ice cream or the like which preferably fills the container to the brim.

45 The closure member shown in Figs. 2, 3 and 4 includes a flat circular disk 10 preferably of cardboard or other fibrous material having an upwardly and inwardly bent peripheral rim portion 11, the flat center of the disk being of greater diameter than the mouth of the shell 20. Co-operating with the disk-like closure member 10 to complete the cap is a flange-forming member indicated generally at 12. This flange-forming member is of annular shape, the cylindrical intermediate portion thereof being of substantially greater diameter than shell 10. The upper edge 45 of member 12 is rolled inwardly and downwardly as indicated at 13 to interlock with the upwardly and inwardly turned rim 11 of the disk 10.

50 The lower portion of the member 12 is rolled inwardly as at 14 and bent upwardly as at 15, this inwardly and upwardly directed bent extension 15 assuming the form of a yielding flap conically tapered at least at the lower end. The lower edge of this flap is of slightly greater diameter than container 20 and the upper edge of 55

the flap may be of substantially less diameter than container 20 so that the container mouth cams into the tapered flap as indicated in Fig. 3 and substantial flexure of the flap occurs as an incident of forcing the cap fully home to the position of Fig. 4.

The upper edge of flap 15 contacts or approximately contacts the disk 10 and thus coats with rolled over portion 13 of member 12 to lock the disk in place. The rounding of integral connection at 14 between the cylindrical portion of member 12 and the flap 15 facilitates the automatic centering (by a camming action) of the closure with respect to the container mouth as the closure is applied. No manual manipulation for "fitting" the closure to the shell is required.

The bending of portions 13, 14 and 15 of member 12 appreciably stiffens this flange forming element so it has no tendency to lose its circular shape even though made of relatively light material. The ice cream which fills the container 20 reinforces this shell and sustains its shape and permits the shell to positively expand the flap 15 as the closure is pressed home. As seen in Fig. 4 no air space is present between the flat disk 10 (which makes complete peripheral contact with the container mouth) and the contents of the container. Thus as pull is exerted to remove the cap there is a tendency to create a vacuum between this disk and the ice cream which affords further resistance to removal of the closure.

In Figs. 5 to 7 I have illustrated a slightly modified form of the invention in which an annular member 16 corresponding to member 12 cooperates with a disk 17 corresponding to disk 10 to constitute the closure. In this case the disk 17 is entirely flat; the upper edge of the annulus 16 is turned or rolled inwardly and downwardly as at 18 to engage the upper edge of the disk 17, and the lower portion of the annulus 16 is turned inwardly and upwardly to provide an annular flap 19 to engage the lower edge of the disk 17. With this form of the invention, the upwardly extending portion 19 of the annulus inclines inwardly at least at its lower end. Here again the intermediate portion member 16 and the upwardly turned portion flap 19 are integrally connected by a rounded connective section 21 which cams over the mouth of the container and centers the cap with respect thereto.

As the cap is forced home this flap 19 is expanded and tensioned, being forced into approximately cylindrical shape and tightly gripping the container 20. In this case again the closure is forced home until the disk 16 abuts the container mouth and contacts the contents of the filled container.

With both forms of the invention, the closure is of two-piece construction and in each case the disk is locked in place by the inwardly and oppositely turned edges of the flange forming piece. Thus the casual handling of the caps or closures prior to their application to the container will not result in dis-assembly of the disks with respect to the flange forming elements. Glue or other adhesive may be employed particularly between the parts 11 and 13 of the form shown in Figs. 2, 3 and 4. With both forms of the invention also the container may be of regular cylindrical form, the only member which is distorted as an incident of the application of the cap being the annular concealed tapered flap of the cap itself.

In the drawing the thickness of the material 75 and the extent to which the flap is flexed as the

cap is applied has been to some extent exaggerated in order to more clearly visually depict the action which occurs.

Having thus described my invention, what I claim as new and desire to secure by Letters Patent is:—

1. A two piece cap of fibrous material adapted to serve as a closure for a cylindrical container, said cap including a flat disk of greater diameter than the container to which the cap 10 is to be applied, and an annular flange forming piece including a cylindrical band extending above and below said disk, the upper edge portion of said band being bent downwardly and inwardly to form an upstanding peripheral bead 15 to engage the upper surface of said disk, and the lower edge portion of said band being bent upwardly and inwardly to form a radially yielding flap to cam over the mouth of the container as the cap is forced home to the extent limited by 20 said disk and to frictionally grip the periphery of the container, the opposed edges of said band abutting opposite surfaces of said disk to hold said disk and said flange forming piece in predetermined relationship. 25

2. A package including a cylindrical container of uniform diameter throughout its length and formed of fibrous material, a bottom therefor, a plastic comestible normally liquid at body temperature filling said container and having its upper surface flush with the upper surface of the latter, and a flanged cap closing the mouth of said container and including a flat disk portion of greater diameter than said container and having complete peripheral contact with said edge 30 and with the surface of said comestible, and a cylindrical band encircling said disk and extending above and below the latter, the upper edge of the disk being bent downwardly and inwardly to form an upstanding peripheral bead, and the lower edge of the band being bent inwardly and upwardly, the opposed edges of said band abutting opposite surfaces of said disk to hold said band and disk in predetermined relationship, and the inwardly and upwardly turned portion of said band being radially yielding to frictionally grip the periphery of the container. 40

3. A package including a cylindrical container of uniform diameter throughout its length and formed of fibrous material, a bottom therefor, a plastic comestible normally liquid at body temperature filling said container and having its upper surface flush with the upper surface of the latter, and a flanged cap closing the mouth of said container and including a flat disk portion 5 of greater diameter than said container and having complete peripheral contact with said edge and with the surface of said comestible, and a cylindrical band encircling said disk and extending above and below the latter, the upper edge 6 of the disk being bent inwardly and downwardly to form an upstanding peripheral bead, and the lower edge of the band being bent inwardly and upwardly to form a flange, said flange having its upper edge adjacent to said disk radially yielding to frictionally grip the periphery of the container. 60

4. A two piece cap of fibrous material adapted to serve as a closure for a container having its peripheral wall cylindrical and flangeless at its upper portion, said cap having a flat disk of greater diameter than said container and provided with an upstanding peripheral flange, and a cylindrical band encircling said disk and ex- 70

tending above and below said disk, the upper portion of said band being bent radially inwardly and downwardly over said flange to form an upstanding peripheral bead and to connect together said band and said disk, and the lower edge portion of said band being bent upwardly and radially inwardly to form a radially yield-

ing flap unsupported intermediate of its upper and lower edges and having its upper edge free to move outward radially toward the body of said band during the application of said cap to said container and by the camming action of the wall of said container. 5
